LIFE PRESERVING SUIT

Filed July 13, 1929

INVENTOR

Albert D. Shave,

John Harleth
his Attorney

UNITED STATES PATENT OFFICE

ALBERT D. SHAVE, OF PORT AUX BASQUES, NEWFOUNDLAND

LIFE-PRESERVING SUIT

Application filed July 13, 1929. Serial No. 378,133.

This present invention relates to new and useful improvements in a life preserving suit and has for its primary object the provision of a simple structure which may be readily 5 stepped into and thus automatically secured on the limbs and shoulders and the sides then instantly closed from the lower edge to the upper edge by a single movement of a quick fastener at each side connecting the front and 10 rear inflatable members.

Another object of the invention resides in the provision of a life preserving suit of the character stated in which the limb encircling members depend from the body of the suit at 15 the sides thereof while the shoulder engaging members are hollow and serve to connect the interior of the inflatable front and rear body members.

A further object of the invention resides in 20 the provision of a life preserving suit of the character stated which is of extremely simple and inexpensive construction, composed of the minimum number of parts and which may be inflated at both front and rear by an air 25 pump carried on the front inflatable body member either before or after the suit is put on.

To the accomplishment of these and related 30 objects, as shall become apparent as the description proceeds, my invention resides in the construction, combination and arrangement of parts, as shall be hereinafter more fully described, illustrated in the accompanying drawings and pointed out in the claim 35 hereunto appended.

The invention will be best understood and can be more clearly described when reference is had to the drawings forming a part of this disclosure wherein like characters indicate 40 like parts throughout the several views.

In the drawings:—

Figure 1 is a perspective view of the improved life preserving suit;

Figure 2 is a detail transverse vertical section through the front body member of the suit; and

Figure 3 is an elevation showing the suit in position on a person.

Referring more in detail to the drawings, it 50 will be noted that the suit includes corre-

sponding inflatable front and rear body members 6 which are secured together at their lower corners 7 and are adapted to be brought together from their lower corners 7 to their upper corners 8 either before or after the suit is put on, by quick fasteners 9 such as the zipper type. The only other connection between the front and rear body members 6 is effected by the hollow shoulder straps 10 having their opposite ends secured in the upper edges of 55 the front and rear body members 6, thus forming communication between the interior of the body members 6 to assure inflation or deflation of these body members 6 together. To provide for inflation and quick deflation of 60 the body members 6, a small hand operated air pump 11 is carried on the front body member 6 and an exhaust valve 12 is associated therewith which may be readily opened for 65 deflating the body members 6, as desired. For retaining the suit firmly in position on the body of the wearer and limiting upward movement of the suit on the wearer, the limb 70 encircling bands 13 are secured to the inner face of the depending straps 14, projecting 75 from the lower portion of the suit at the sides thereof.

As the construction of the device has thus been described in detail, brief reference is now had to its use and modus operandi: 80 When the suit is deflated, the shoulder straps 10 fall to the side and the front and rear body members 6 separate, except at their lower corners. This makes it very easy for the person to step into the suit by inserting 85 the feet through the bands 13 and drawing the latter upwardly on the limbs, then inserting the arms below the shoulder straps 10 and thus causing the latter to assume proper position on the shoulders. It then only 90 remains necessary to give a quick upward pull on each of the quick fasteners 9 at the sides of the suit and thus complete the operation of securing the suit firmly in position. The air pump 11 may be operated at any time desired and a few rapid strokes or 95 operations thereof will be sufficient to inflate both the front and rear body members 6 and the shoulder straps 10 forming communication between the front and rear body mem- 100

bers 6. When the shoulder straps 10 are inflated with the body members 6, the straps will remain in normal position over the shoulders of the wearer and will also co-operate with the front and rear body members 6 in maintaining the wearer of the suit at or near the water surface. Owing to the location of the bands 13 around the upper portions of the limbs, the suit will be held in place and not only prevented from working up on the body of the wearer but will also be held against turning thereon. When air is not required in the body members 6 and shoulder straps 10, of the suit, the valve 12 may be opened to exhaust the air. This may be desirable when removing the suit from the wearer or when placing the suit in position on the wearer.

From the foregoing description taken in connection with the accompanying description, it will be manifest that a life preserving suit is provided that will fulfill all the necessary requirements of such a device, but as many changes could be made in the above description and many apparently widely different embodiments of my invention may be constructed within the scope of the appended claim without departing from the spirit or scope thereof, it is intended that all matters contained in the said accompanying specification and drawings shall be interpreted as illustrative and not in a limited sense.

Having thus described my invention, what I claim as new and desire to secure by Letters Patent is:—

A life preserving suit including front and rear inflatable body members; a combined manually operable inflating device and exhaust valve carried on said front body member; hollow shoulder straps connecting the upper edges of said front and rear body members and formed therewith; said front and rear body members being permanently connected at their lower corners; quick fastening means for closing the opposed vertical edges of said front and rear body members from the lower corners to the upper corners thereof; straps depending from one of said body members adjacent the connected lower corners thereof; and continuous circular limb encircling members carried on the lower ends of said last mentioned straps.

In testimony whereof I hereunto affix my signature.

ALBERT D. SHAVE. [L. S.]
